Fraser, Turk & Nease
ATTORNEYS,

INVENTOR :

UNITED STATES PATENT OFFICE.

HENRY STANLEY HORN, OF EAST ORANGE, NEW JERSEY.

LOOSE-LEAF BINDER.

Application filed April 17, 1922. Serial No. 553,820.

To all whom it may concern:

Be it known that I, HENRY STANLEY HORN, a citizen of the United States of America, residing in East Orange, in the county of Essex and State of New Jersey, have invented certain new and useful Improvements in Loose-Leaf Binders, of which the following is a specification.

The present invention relates to loose leaf binders or the like, and aims to provide certain improvements therein.

An object of the present invention is to provide a device of the class described, which will be adapted to hold loose leaves securely in place and which may be adjusted to accommodate a greater or less number of leaves. It is also an object of the present invention that the device be simple in construction, effective in operation, and one that may be manufactured and sold at a low price.

To this end the invention comprises a loose leaf device having a binder consisting of a pair of adjustable telescopic members, one of which is tubular and provided with lateral openings in its side, and the other of which is formed with a pair of spring fingers formed at their free ends with a lateral projection adapted to enter an opening in the tubular member. The invention also contemplates the combination of such binder post with a substantially semi-circular element which may serve to hold the leaves and which is preferably formed to have a quick detachable connection with said binder post. Certain other features of improvement are also contemplated, and will be hereinafter more fully set forth.

Referring to the drawings, wherein I have shown the preferred embodiments of my invention,

Figure 1 is a transverse section of a loose leaf device showing my invention embodied therein.

Fig. 2 is a similar view showing the telescopic binder elements in contracted position.

Fig. 3 is an elevation of the telescopic binder elements in separated position.

Fig. 4 is a transverse section taken on the line 4-4 of the tubular element shown in Fig. 3.

Fig. 5 is a transverse section taken on the line 5-5 of Fig. 2.

Fig. 6 is a similar section showing the position of the spring fingers in disengaging position.

Fig. 7 is a transverse section showing the employment of a separate extension member.

Fig. 8 is a side elevation of the extension member shown in Fig. 7.

Referring first to Figs. 1 to 6 of the drawings, let A and A' indicate the covers and B the back of a loose leaf binder. The back and covers are preferably flexibly connected together, as shown at C.

For the purpose of holding the leaves between the binder covers, I employ a substantially semicircular or U-shaped element D. It is preferable that this element be resilient and provided with an initial outward tension tending to move its ends apart for a purpose to be hereinafter set forth. This element is preferably carried by a binder post formed of a pair of telescopic sections E and F, and acts against said binder post adjacent its ends to urge the telescopic members thereof apart. While any suitable connection between the binder post members and the element D may be resorted to, I prefer to employ the connection herein disclosed, which consists in one end of the element D being looped around the post F, as shown at d, and the other end being formed with notches d' adapted to engage and hold against the lowermost edge of one of the grooves e. The element D being resilient and provided with an initial outward tension, it will be appreciated that by the means just described a quickly attachable and detachable connection between the binder post and the element D is provided. To accommodate different thicknesses of leaves between the covers, members E and F are made longitudinally adjustable. This is accomplished by forming the member E, which is tubular, with a plurality of openings e in its side, and forming the member F with a pair of spring arms f, f', the free ends of said arms being each provided with a lateral catch projection f² adapted to engage in the openings e of the tubular member E, owing to the initial outward tension possessed by the spring fingers f, f'.

The members E and F may be carried by the back member B in any suitable manner, but I have found that by permanently se-

curing the head e' of the tubular member to said back, as shown at G, and having the member F bodily movable through a suitable eyelet H in the back member, satisfactory results are obtained. To facilitate the easy movement of the catch projections f^2 through the tubular member, the underside of said projections are preferably beveled, as indicated at f^3 , and to provide for the facile disengagement of said catch projections from the opening e , the sides of said projections are beveled, as indicated at f^4 , as best shown in Fig. 6. It will thus be seen that when the projections are in locking engagement with the openings in the tubular member, that by turning the member F through an angle of 90° , a complete disengagement is accomplished. Such turning movement may be accomplished by rotating the head f^5 either with the fingers or by applying any suitable instrument to the kerf f^6 in the head f^5 .

In Fig. 7 I have shown the employment of an additional extension member I co-operating with the telescopic members E and F. By the employment of such extension member, the binder device may be made to accommodate an amount of leaves of greater thickness than the maximum degree of extension when only the elements E and F are employed. This extension member I in construction embodies the features of both the telescopic members E and F, and is adapted to simultaneously telescope with both of said members. In construction it consists of a tubular part J having openings j in its side, and a pair of spring fingers K each formed at its free end with a lateral projection k . The parts J and K are substantially the same in construction as the parts E and F respectively, and in use the part J is adapted to receive the binder post member F, while the part K is adapted to enter and be received by the binder member E. A resilient member D' may be used in combination with this binder post, in the same way as with that disclosed in Fig. 1.

In the use of the device, the leaves are carried by the element D and the binder post members E and F telescoped together to the proper degree, depending on the amount of leaves held by said element. In varying the effective length of the telescoping members E and F, the effective length of the element D, that is the length of the chord joining the ends of said element is also varied, but the effective length of the element D which is necessarily different for every adjustment of the members E and F does not vary when the covers of the device are opened or closed. When it is desired to add or remove any leaves, the cover is opened and the end adjacent the notches d' made free by applying there-

to a slight upward pressure. After the addition or removal of leaves, the telescoping members E and F are respectively withdrawn or contracted, as found necessary, and the notch d' again caused to engage in the wall of the opening e .

While in the embodiments of the invention herein disclosed the element D is primarily designed to hold the leaves, it will be appreciated that, if desired, this element may be dispensed with and the leaves directly held by the binder post elements. In this event, when it is desired to add or remove leaves, the binder post member F must be entirely withdrawn from the tubular member E. However, if the leaves are formed with slotted openings a complete separation of the binder post elements is not necessary, but a mere extension of said members would suffice to permit the addition or removal of such leaves. Hence, it will be appreciated that the present invention contemplates the use of the binder post elements with or without the semicircular leaf-holding element.

While I have shown and described the preferred embodiments of my invention, it will be understood that I do not wish to be limited to the specific construction herein set forth, since various changes therein may be resorted to without departing from the spirit of the invention.

What I claim is:

1. A loose leaf binder comprising a pair of telescopic members having interengaging means and a resilient element connected with said members adjacent their remote ends.

2. A loose leaf binder comprising a pair of telescopic members having interengaging means, and a resilient element adapted to hold the leaves connected with said members adjacent their remote ends and acting to urge them apart.

3. A loose leaf binder comprising a binder post and a substantially semi-circular element for holding the leaves, one end of the semi-circular element having a quickly detachable connection with the binder post.

4. A loose leaf binder comprising a pair of adjustable telescopic members, one being tubular and formed with a longitudinal series of openings in its side, and the other having a pair of spring fingers formed at their free ends with a catch projection adapted to enter an opening in the first member to lock the member against separation, the catch projections being beveled on their under side to freely ride through the tubular member, and beveled at their sides so that by slightly rotating the spring finger carrying member the catch projection will be released from the opening.

5. A loose leaf binder comprising a pair of members adapted for telescopic connec-

tion with each other and an extension member adapted to simultaneously telescope with the pair of members, said extension member having a tubular portion provided with openings in its side and a pair of spring fingers formed at their free ends with a catch projection, the tubular portion being adapt-

ed to receive therein one of the pair of members, and the spring fingers adapted to enter the other of the pair of members. ¹⁰

In witness whereof, I have hereunto signed my name.

HENRY STANLEY HORN.
